REMOTE CONTROL SYSTEM

Harmon B. Deal, Glen Ridge, N. J., assignor to
 Radio Corporation of America, a corporation
 of Delaware

Application July 23, 1941, Serial No. 403,736

10 Claims. (Cl. 250—2)

The present invention relates generally to remote control systems, and more particularly to a remote control system wherein the operation of a reproducer of a "standby" radio receiver may be controlled from a remote point transmitting a carrier wave modulated by normal modulation frequencies and special control modulation frequencies.

It is, of course, obvious that in times of national emergency it may be of vital importance immediately to broadcast to the people of the nation, or to a certain class of people such as air wardens, an impending condition or action and to issue necessary instructions to them. The scheme contemplated herein is feasible from all viewpoints for either the sound broadcast band or the ultra-high frequency band. In accordance with the present invention, control signals which are preferably, though not necessarily, generated at the broadcast station are utilized to modulate the carrier of the broadcast station which is to exercise control. Of course, if desired, an auxiliary special carrier may be modulated.

If a remote receiver is to be controlled as described above, and the station's regular carrier is to be modulated by the control signals, it is immaterial whether or not the controlling signals are audible since the control signals would normally precede the start, and follow the termination of the special broadcast. However, it is evident that under certain circumstances, an inaudible control signal is to be preferred, as for example in the case where there may have been in progress a program to which many people were already listening and to whom an audible control signal would be objectionable, or in cases where a certain amount of secrecy is desirable.

Inaudibility of the control signal may be obtained by utilizing super-audible or sub-audible control frequencies. Since super-audible frequencies would encroach on adjacent broadcast channels, sub-audible control frequencies are preferred. Another reason for preferring the sub-audible frequency band for the control frequencies is because it is immediately available since it is not being used presently. The average radio receiver and loud-speaker cut off below 100 cycles per second, and even the very best receivers with considerable bass compensation do not transmit frequencies below 50 cycles per second to any appreciable extent. This indicates that a band in which control signals will not affect program material being broadcast simultaneously, lies below 50 cycles per second. It is recognized, of course, that the low frequency

cut-off of a receiver is not abrupt, and that therefore the lowest usable frequency and amplitude of the control signals will produce the least program interference.

5 In a series of tests which have been conducted with devices built in accordance with the present invention, it has been found that the amplitude of the control signals should be kept as small as possible for the reason that harmonics of the control frequency, whether originating in the source or produced in the receiver, will lie in the acceptance band of the usual radio receiver and will be audible. The harmonics may be produced in the receiver by overload or by cross-modulation of control frequencies and program, and it has been determined that both of these effects are considerably aggravated by large control signal amplitudes.

20 Briefly, the invention provides means at the transmitter for producing the control frequencies which may comprise an oscillation generator tube and modulating means for modulating the carrier of the transmitter with the control signals. At the receiver, which is in "standby" condition means are provided for receiving the modulated carrier and utilizing the derived signals for control purposes.

25 It is believed that the invention will be better understood and its various objects and advantages will be more apparent from the following detailed description of a preferred embodiment thereof when read in conjunction with the attached drawings.

In the drawings:

30 Figure 1 illustrates in diagrammatic form a suitable control signal generating means which may be used as a transmitting station for modulating the transmitter carrier by the control signals in accordance with the present invention; and,

35 Figure 2 is a diagrammatic illustration of a preferred embodiment of a receiver unit adapted to be controlled in accordance with received control signals.

40 Referring now more particularly to Figure 1 of the drawings, there is provided an electronic tube 1 which is employed as an oscillator to generate the various desired control frequencies. For this purpose a novel phase reversal circuit arrangement is used for providing phase reversal between the grid and plate of the oscillator tube 1. The phase reversal network is connected between the anode and cathode of the tube and comprises capacities 7, 8, and 9 and resistors 10 and 11. This network, also, determines the fre-

quency of the generated oscillations in accordance with the values of the resistances and the condensers. Feedback between the plate and the grid is provided by a circuit 24 which connects point 26 of the phase reversing circuit to the input grid of tube 1 through a coupling condenser 3. In order to avoid undesirable phase shifts in the resistance of the grid coupling circuit, a high resistance grid leak resistor 2 is provided.

Preferably the resistance of resistor 2 should be large as compared to the reactance of condenser 3. Two control push buttons 16 and 20 are provided. Push button 20 acts upon depression to close a switch 21, and thereby connects the output of the oscillator 1 to the amplifier 23. Push button 16, on the other hand, acts when depressed to open switches 17 and 18 and close switch 19. Normally resistor 13 is connected in parallel with resistor 11, and, likewise, resistor 14 is connected in parallel with resistor 10. Under these conditions the net resistance between points 25 and 26 of the network is decreased. This results in a higher frequency of oscillation. Consequently, with push button 16 not depressed, and push button 20 depressed, control oscillations of a certain frequency are impressed upon the amplifier 23 through closed switch 21 and conductor 22.

When push button 16 is depressed, the parallel resistors 13 and 14 are disconnected from the phase shifting circuit thereby resulting in a higher net resistance between points 25 and 26 and therefore providing a lower output frequency, it being noted that the new frequency is fed to the same output amplifier 23 through conductor 22 due to closure of switch 19. In the condition shown, the oscillator 1 is operating at a frequency which is determined by resistors 10, 11, 13, and 14, and the oscillations of this frequency will be impressed upon the amplifier 23 upon closure of switch 21. Hence, depression of push button 20 will impress this control frequency upon the transmitter where it is utilized to modulate the carrier of the transmitter in accordance with well known practice.

It should be noted that resistors 10, 11, 13, and 14 are preferably variable resistors so as to permit adjustments. Also, unicontrol means 12 is provided to adjust resistors 10 and 11 simultaneously, and unicontrol means 15 is provided to permit simultaneous adjustments of resistors 13 and 14. If it is desired to transmit the other control frequency, it is only necessary to depress push button 16 as previously described.

For receiving the transmitted energy there may be employed receiving apparatus such as is shown in Figure 2, wherein the usual antenna system 30 is connected to the input of a radio receiver 31 which may be tunable over one or more bands of frequencies if desired, it being noted that the output of 31 comprises the audio output from the detector of the receiver. If a superheterodyne type receiver is used then the output is taken preferably from the second detector. The receiver portions 30, 31, 32 and 42 are, of course, in "standby" condition in order to detect the control frequencies applied over lead 46 to the relays controlling the connecting means for the loud speaker 48, 79. The audio output of receiver 31 is fed to a power output tube 42 through a network 32 which will be more fully described hereinafter.

The output terminals 46, 47 of the output tube 42 are connected to a tuned reed unit which includes a pair of tuned reeds 53, 59, one of which

reeds is responsive to one of the control frequencies whereas the other reed is responsive to the other of the control frequencies. The tuned reeds 53 and 59 are provided with driving electromagnets 52 and 58, respectively. Tuned reed 53 is provided with a sliding weight 79 which may be adjusted along the reed so as to tune the reed to the desired frequency. Vibration of reed 53 causes the intermittent closure of a switch 54 which acts to connect an energizing winding 57 of a double acting locking relay across the power supply line. Reed 59 is also provided with a sliding weight 80 for tuning purposes. Vibration of reed 59 causes intermittent closure of switch 60 which in turn connects the other energizing winding 63 of the locking relay across the power supply line. The relay is provided with an armature 80' which is arranged to snap into either of its two positions depending upon which one of windings 57 and 63 is energized. In the position shown, the relay winding 57 was energized last thereby causing the armature 80' to assume its upward position in which a pair of switches 64 and 65 are maintained in a closed position. Under these conditions, if relay 63 is energized, the armature 80' will snap into its downward position thereby permitting switches 64 and 65 to open and closing switches 66 and 67.

For translating the signals, there is provided a loudspeaker 79 which is connected across switch 65 by means shown generally as a coil 49 so that closure of switch 65 short circuits the speaker input coil 49. In order to provide energizing potentials for the tuned reed apparatus, a plug 69 may be provided which may be plugged into any suitable socket receptacle of a power supply network. Also, a socket receptacle 68 is provided to which may be connected any device which it is desired to control.

In order to insure that low frequency components of the program will not operate the tuned reeds, there is provided a low pass filter composed of elements 35, 36, 37, and 38. This filter operates to effectively cut off all frequencies above approximately 45 cycles per second. For those applications where it is desirable that a loudspeaker be turned on where the loudspeaker is a part of the controlled receiver, an auxiliary network composed of resistor 34, condenser 38, and resistor 41 is included. By making the capacity of condenser 38 small so that its reactance as compared with resistor 41 is high, this auxiliary network operates to pass program frequencies above say 200 cycles per second. This insures that the grid of the power output tube 42 has applied to it low frequency components from the oscillator at the transmitting station and also program signals, but that a band of frequencies from approximately 45 cycles to 200 cycles is eliminated, thus obviating the chance of low frequency components of program such as organ music actuating the reeds. The resistor 38' is shunted across condenser 38 to provide a direct current return path for the input grid of tube 42.

In the operation of the device shown in Figure 2, if the control frequency representative of reproducer operation is impressed upon terminal 46 from tube 42 and the circuit arrangement is in the condition shown in Figure 2, the control energy will be fed to the energizing winding of electromagnet 58 through the following circuit, terminal 46, conductor 48, closed switch 65, conductor 50, conductor 71, closed switch 64, conductor 78, winding of magnet 58, to terminal 47. This means that the control frequency is im-

pressed upon the winding of driving magnet 58. If reed 59 is tuned to that particular control frequency, it will start to vibrate causing intermittent closure of switch 60. When this happens the relay winding 63 will be energized through the following circuit, closed switch 60, reed 59, magnet core 58, conductor 75, one side of the power line to one terminal of the power supply, then from the other terminal of the power supply to the other side of the power line, resistor 74, conductor 73, the winding of relay 63, conductor 72, back to switch 60. This will cause armature 80' to be pulled downwardly to its other position thereby opening switches 64 and 65 and closing switches 66 and 67. Closure of switch 67 short circuits the winding of relay 53 so that the reed 59 will stop vibrating. Closure of switch 66 will connect socket receptacle 68 across the power supply line and will thereby energize any desired controlled device. At the same time, the short circuit across speaker coil 49 is removed by the opening of switch 65. Hence, the special broadcast that was the occasion for sending the reproduce control frequency may be reproduced through loud-speaker 79. The broadcast modulation energy is impressed across the input coil 49 of the speaker 79 through the following circuit, terminal 46, conductor 48, voice coil 49, conductor 50, condenser 51 to terminal 47.

When it is desired to render the receiver reproducer ineffective the other frequency is transmitted from the transmitter thereby energizing the relay 52 at the receiver which causes closure of switch 54, and energization of relay 51, thereby bringing back the various switches to the position shown.

While I have disclosed certain preferred embodiments of my invention, it is to be understood that the same is not limited to the details disclosed and that they may be varied within the scope of the appended claims.

What I claim is:

1. In a signalling system of the type wherein the carrier of a transmitter is modulated by modulation signals representative of a special broadcast and at least two auxiliary modulation signals representative of the beginning and end of the special broadcast, a single receiver including settable means, responsive to said auxiliary signals in the detected output of the receiver, acting upon receipt of one of said auxiliary signals to condition the receiver reproduction so as to render the special broadcast signal intelligible, said settable means acting upon receipt of another of said auxiliary signals to condition the receiver reproduction so as to render the special broadcast signals unintelligible.

2. In a signalling system wherein means are provided at the transmitting station for generating a plurality of different auxiliary frequencies which are independent of the program frequencies and lower in frequency than the lowest program frequency to be transmitted, one of said auxiliary frequencies being transmitted to indicate that a special program transmission is about to take place and another of said auxiliary frequencies being transmitted to indicate the end of the special program transmission, a receiver tuned to receive the modulated carrier energy transmitted from said transmitter, said receiver including a detector, a detected signal translating device and relay means, means for coupling the detector output to the relay means comprising a low pass filter circuit adapted to pass only frequencies which are below the lowest program fre-

quency, an additional circuit arranged to pass only frequencies above the lowest program frequencies, and an operable switching device for connecting the translating device to said additional circuit whereby the program frequencies are fed to the translating device.

3. In a receiver of the type adapted to collect modulated carrier waves which have included in the modulation at least one sub-audible control frequency representative of one desired condition of the receiver, said receiver including means to provide demodulation of the collected waves thereby to provide said control frequency, and means to reproduce demodulated wave energy; the improvement which comprises a device for controlling the effectiveness of said reproducer means, means for controlling the operation of said device, and means selectively operable by said control frequency for actuating said last control means, and additional means, responsive to actuation of said device control means, for rendering effective an electrical circuit.

4. In a receiver of the type adapted to collect modulated carrier waves which have included in the modulation at least one sub-audible control frequency representative of one desired condition of the receiver, said receiver including means to provide demodulation of the collected waves thereby to provide said control frequency, and means to reproduce demodulated wave energy; the improvement which comprises a device for controlling the effectiveness of said reproducer means, means for controlling the operation of said device, and means selectively operable by said control frequency for actuating said last control means, and additional means, responsive to actuation of said control means, for rendering said selectively operable means ineffective.

5. In a receiver of the type adapted to collect modulated carrier waves which have included in the modulation at least one sub-audible control frequency representative of one desired condition of the receiver, said receiver including means to provide demodulation of the collected waves thereby to provide said control frequency, and means to reproduce demodulated wave energy; the improvement which comprises a device for controlling the effectiveness of said reproducer means, means for controlling the operation of said device, and means selectively operable by said control frequency for actuating said last control means, said selectively operable means consisting of a reed tuned to said control frequency, and electromagnetic means for vibrating said reed in response to energy of said control frequency.

6. In a receiver of the type adapted to collect modulated carrier waves which have included in the modulation at least one sub-audible control frequency representative of one desired condition of the receiver, said receiver including means to provide demodulation of the collected waves thereby to provide said control frequency, and means to reproduce demodulated wave energy; the improvement which comprises a device for controlling the effectiveness of said reproducer means, means for controlling the operation of said device, and means selectively operable by said control frequency for actuating said last control means, a second means selectively operable by a different sub-audible control frequency included in said modulation in place of said first control frequency, a second means, controlling the operation of said reproducer control device, adapted to be actuated by said second selectively operable means.

7. In a receiver of the type adapted to collect modulated carrier waves which have included in the modulation at least one sub-audible control frequency representative of one desired condition of the receiver, said receiver including means to provide demodulation of the collected waves thereby to provide said control frequency, and means to reproduce demodulated wave energy; the improvement which comprises a device for controlling the effectiveness of said reproducer means, means for controlling the operation of said device, and means selectively operable by said control frequency for actuating said last control means, a second means selectively operable by a different sub-audible control frequency included in said modulation in place of said first control frequency, a second means, controlling the operation of said reproducer control device in a sense opposed to the control of said first device control means, adapted to be actuated by said second selectively operable means.

8. In a radio signalling system including a receiver upon whose input terminals are applied modulated carrier waves whose modulation signals include at least one control frequency representative of a desired state of effectiveness of the receiver, said receiver including detection means for deriving energy of said control frequency from the waves, a control device for controlling the effectiveness of the receiver, an electromagnetic device including an energizing circuit for actuating said control device, a selective reed means, tuned to said control frequency, for controlling the said energizing circuit, and means, responsive to said derived control frequency energy, for intermittently controlling said selective means.

9. In a radio signalling system including a

receiver upon whose input terminals are applied modulated carrier waves whose modulation signals include at least one control frequency representative of a desired state of effectiveness of the receiver, said receiver including detection means for deriving energy of said control frequency from the waves, a control device for controlling the effectiveness of the receiver, an electromagnetic device including an energizing circuit for actuating said control device, a selective means, tuned to said control frequency, for controlling the said energizing circuit, and means, responsive to said derived control frequency energy, for controlling said selective means, and additional means, responsive to energization of said electromagnetic device and actuation of the control device, for preventing operation of the means for controlling the selective means.

10. In a radio signalling system including a receiver upon whose input terminals are applied modulated carrier waves whose modulation signals include at least one control frequency representative of a desired state of effectiveness of the receiver, said receiver including detection means for deriving energy of said control frequency from the waves, a control device for controlling the effectiveness of the receiver, an electromagnetic device including an energizing circuit for actuating said control device, a selective reed, tuned to said control frequency, for controlling the said energizing circuit, and means, responsive to said derived control frequency energy, for controlling said selective reed, and a filter network following said detection means for prevention of transmission of modulation energy of from approximately 45 to 200 cycles.

HARMON B. DEAL.
